INVENTOR,

Frank A. Fouts

UNITED STATES PATENT OFFICE.

FRANK A. FOUTS, OF WASHINGTON, DISTRICT OF COLUMBIA.

CIGAR-HOLDER.

SPECIFICATION forming part of Letters Patent No. 368,466, dated August 16, 1887.

Application filed June 9, 1887. Serial No. 240,680. (No model.)

To all whom it may concern:

Be it known that I, FRANK A. FOUTS, a citizen of the United States, residing at Washington, in the District of Columbia, have invented 5 certain new and useful Improvements in Cigar-Holders; and I do hereby declare the following to be a full, clear, and exact description of the invention, such as will enable others skilled in the art to which it appertains to 10 make and use the same.

My invention is a cigar-holder, and it is an improvement on the article shown and claimed in my Letters Patent of the United States No. 364,504, dated June 7, 1887.

15 My present improvement relates to a cigar-holder having a body formed of an elastic or flexible plate or sheet, said body being provided with a handle and an opening for the reception of a cigar, the edge of said opening 20 being yielding or flexible, so as to conform to cigars of different diameters, the inner part of the body of said holder being provided with radial slits communicating with the opening aforesaid and a cut through said body, where- 25 by jaws are formed which may be parted and the opening in the holder enlarged, the face immediately around said opening, or the edge thereof, or both, being provided with a material adapted to protect the body from fire or 30 heat, all of which will be fully hereinafter specified, and pointed out in the claims.

The holder is preferably formed of india-rubber or other elastic or flexible material. It is in the nature of a shield, being adapted to 35 protect the mustache and lips of the smoker from the fire end of a cigar.

In the accompanying drawings, Figure 1 represents a front view of the face of the cigar-holder, the jaws being closed in their normal 40 position; and Fig. 2 is a rear view thereof, with the jaws sprung apart so as to enlarge the central opening. Fig. 3 is a sectional view taken on the line X X of Fig. 1. Fig. 4 represents an edge view of the holder, one of 45 the jaws being raised above the line of its companion jaw. Fig. 5 represents an edge view of the holder with a partly-smoked cigar therein; and Fig. 6 is a perspective view of the holder and partly-smoked cigar, the inner end of the 50 cigar and holder being at rest upon a flat surface, the fire end of the cigar being elevated above the surface.

In the accompanying drawings like letters indicate corresponding parts in the several views.

The letter A represents the body of the holder, shown in the form of a disk, and B is a handle, formed integral with the body A and extending outward therefrom. C indicates a central opening in said body for the 60 reception of a cigar. A circumferential ledge or recess, D, is formed around the opening aforesaid. This recess is formed by a depression in the face of the body A around the opening. The depression being on one side 65 of the body only, leaves the material along the edge of the opening or wall thinner than the body portion, so that this edge will readily yield and conform to a cigar when inserted into the opening without expanding or affecting the body portion, which is comparatively 70 thick and firm. The recess formed by said depression is filled in or coated with a layer of asbestos or asbestos paint or other incombustible material, or material which will protect the body of the holder from fire and heat 75 when a cigar is consumed down to the outer face of the holder. The edge of the opening is also coated or protected. Of course it is not intended to smoke a cigar so close as to 80 bring the fire end thereof into contact with the holder. If, however, such should occur, the body of the holder will be protected by the incombustible material aforesaid.

The letter F represents a cut completely 85 through the body of the holder, so as to enable a smoker to separate the jaws formed by said cut and enlarge the central opening in the holder for the purpose of admitting or discharging a cigar therefrom. It is not desirable 90 to handle a cigar when the same is burned to a small fragment. Therefore, when a cigar is so reduced the smoker may discharge the same from the holder by opening the jaws. In practice the diameter of the opening in the 95 holder is smaller than the diameter of the average cigar, so that when the cigar is inserted into said opening the edge thereof will yield and conform to the diameter of the cigar and securely hold and clamp the same.

In order to render the edge of the opening or that portion which binds the cigar more yielding, flexible, or elastic, I provide the inner part of the holder with a series of slits,

These slits communicate with the opening aforesaid, and they extend outward radially, whereby yielding sections are formed.

Having thus described my invention, I claim 5 as new and desire to secure by Letters Patent of the United States--

1. As an article of manufacture, a cigar-holder consisting of a plate or sheet provided with a handle and an opening for the reception 10 of a cigar, and also provided with a cut through the body, substantially as specified.

2. As an article of manufacture, a cigar-holder consisting of a sheet or plate having a handle and provided with an opening for the 15 reception of a cigar, the inner wall or edge of said opening being more flexible or yielding than the outer or body portion, said plate being also provided with a cut through its body, substantially as specified.

20 3. As an article of manufacture, a cigar-holder consisting of a sheet or plate provided

with an opening for the reception of a cigar, and with slits partly through the inner wall or body, which communicate with the opening aforesaid, said plate having a cut through its 25 body and being provided with a handle, substantially as specified.

4. As an article of manufacture, a cigar-holder consisting of a plate or sheet provided with a handle and an opening for the reception 30 of a cigar, also provided with a cut through the body, the inner wall or edge of the opening aforesaid being provided with fire or heat resisting means, substantially as specified.

In testimony whereof I affix my signature in presence of two witnesses.

FRANK A. FOUTS.
